UNITED STATES PATENT OFFICE

101,665

DESIGN FOR A RADIO TABLE HEAD

Leon Beaumon, Los Angeles, Calif.

Application March 23, 1936, Serial No. 61,748

Term of patent 14 years

To all whom it may concern:

Be it known that I, Leon Beaumon, a citizen of the United States, residing at Los Angeles, in the State of California, have invented a new, original, and ornamental design for Radio Table Head, of which the following is a specification, reference being had to the accompanying drawing, forming part thereof, in which:

Fig. 1 is a top perspective view of the table head, and,

Fig. 2 is a bottom perspective view of the table head.

I claim:

The ornamental design for a radio table head, substantially as shown.

LEON BEAUMON.
